UNITED STATES PATENT OFFICE

119,195

DESIGN FOR AN OVERSHOE

Lucille B. Fitzgerald, Naugatuck, Conn., assignor to United States Rubber Company, New York,
N. Y., a corporation of New Jersey

Application January 11, 1940, Serial No. 89,396

Term of patent 3½ years

To all whom it may concern:

Be it known that I, Lucille B. Fitzgerald, a citizen of the United States of America, residing at Bristol Terrace, Naugatuck, county of New Haven, State of Connecticut, have invented a new, original, and ornamental Design for an Overshoe, of which the following is a specification, reference being had to the accompanying drawing, forming part thereof, wherein:

I claim:

The ornamental design for an overshoe, as shown.

LUCILLE B. FITZGERALD.
